Frederick E. Neef, Jr., United States Army,
Baltimore, Md.

Application June 20, 1942, Serial No. 107,268

Term of patent 3½ years

To all whom it may concern:

Be it known that I, Frederick E. Neef, Jr., United States Army, a citizen of the United States, residing at Baltimore, Maryland, have invented a new, original, and ornamental Design for a Portable Fuel Dispenser Frame, of which the following is a specification, reference being had to the accompanying drawings, forming part thereof.

Fig. 1 is a perspective view of a portable fuel dispenser frame, showing my new design,
Fig. 2 is a plan view,
Fig. 3 is a side elevational view, and
Fig. 4 is an end elevational view thereof.

I claim:

The ornamental design for a portable fuel dispenser frame, as shown.

FREDERICK E. NEEF, JR.
